P. M. Martz,
Planing and Matching Machine.
Patented June 25, 1830.

P. M. Marty, of the Borough of Indianapolis, Indiana.

Letter Patent.

The schedule referred to in these Letters Patent and making part of the same containing a description in the words of the said P. M. Marty, how 1/4 of his improvement in the machine for planing, Tonguing and Grooving Flooring Planks,

To all to whom these presents shall come, - Be it known that I, P. M. Marty, of the Borough of Indianapolis in the County of Marion and State of Indiana, have invented a new and useful Planing Mill, for the purpose of Planing, Tonguing and Grooving Flooring Boards, and that the following is a full and exact description thereof:

Frame - 12 feet long, 3 feet 4 inches high, 4 feet 6 inches wide, all made of something 6 by eight inches framed with hemlock and mortised and made fast by iron bolts or keys. The grand pulley or band wheel marked A. 1. on its profile, being 15 inches in diameter, and is made fast on the one end of an iron shaft 10 feet 6 inches long 1 1/2 inches square and has horizontal holes in the lower part of the frame near the one end, - The said pulley or band wheel being fastened by band from either steam, water, or horse power. - Pulley or band wheel A. 2. being fast on same shaft and is 22 inches in diameter and by band gives motion to A. 3. - Pulley or band wheel A. 3. being 15 inches in diameter and is made fast on an iron shaft which has holes 2 1/2 inches apart on the shaft of the frame, and is 2 feet long 1 1/2 inches square and gives motion to A. 4. to on same shaft, and is 20 inches in diameter, and by band gives motion to 2 pulleys or band wheel marked A. 5. - Pulley or band wheel A. 6. being 12 inches in diameter and is made fast on an iron shaft, 3 feet long 1 1/2 inches square and having verticals on the outside of the frame near opposite

to the cartier and gives motion to ab. 38 on same shaft and is 20 inches in diameter and by bands give motion to 2 pulleys or band wheels ab. 16 and 1 ab. 11. Pulley or band wheel ab. 16 being 5 inches in diameter made fast on 2 iron shafts 14 feet 6 inches long 1 $\frac{1}{2}$ inches in diameter and lay horizontal across the top of the frame immediately over each other, on which shafts knives or cutters are made fast, which touch the tongue and make straight the other edge of the board prepared for the groove to be cut therein. These cutters are made fast by screws and tops prepared to be set for wide and narrow boards. Pulley or band wheel ab. 11 being 5 inches in diameter and made fast on 2 iron shafts 2 feet 6 inches long 1 $\frac{1}{2}$ inches square and stand vertical at ^{the} edge of each board, on same shaft the cutters are made fast by screws and tops and makes the groove into the edge of each board. Pulley or band wheel ab. 16, being 10 inches in diameter, and is made fast on a cast iron shaft 3 feet 8 inches long and 2 inches in diameter, and stands vertical within 18 inches of the one edge of the frame and opposite to the centre on which shaft there is a cast iron trim made fast which has 4 arms on which arms are made fast by screws bolts 1 $\frac{1}{2}$ inches or cutters 8 inches long and stand 2 inches down, the lower edge of the knives being lined with steel and made sharp to plane the boards, as they pass through between the edge of the cutters and the frame. The vertical shaft on which the knives or cutters are made fast stands with the lower end in a step on a bridge-tree. That by keys the same may be raised or lowered according to the thickness of the boards, which the knives or cutters are to plane. The upper end of said shaft is made fast by box and binder on a lifting rod made of cast iron extending across the frame each end made fast on each edge of the frame by screws bolts. Two boards, pass on this top of the frame under the knives or cutters one on each side of the vertical shaft. The knives or cutting marked ab. 16 plane the boards to a thickness as they pass. The cutters on the shaft on which the band wheel ab. 16 and ab. 11 are made fast they make the tongue and groove and the pass. The boards are put into motion by rollers made of wood and iron shaft.

expanding through them on which shafts are made fast 3 band wheels No. 13, No. 14, and No. 15 are Pulley or band wheel A. 9, being 28 inches in diameter and is made fast on an iron shaft 4 feet 6 inches long and lays horizontal across the frame and gives motion to A. 10 on same shaft being 5 inches in diameter and by band gives motion to A. 11 Pulley on band wheel A. 11 being 10 inches in diameter and is made fast on an iron shaft 4 feet long 1 $\frac{1}{2}$ inches square and lays horizontal across the frame and gives motion to 2 wheels A. 12 being 18 inches in diameter and by bands gives motion to 2 wheels No. 13, being 20 inches in diameter and gives motion to A. 14, being 20 inches in diameter and by band gives motion to A. 15 being 20 inches in diameter and made fast on the iron shafts expanding through the rollers made wood 14 inches in diameter iron pinty put therein and gives motion to 2 boards that the machine is then operating on. The two boards enter at the one end of the machine on the top of the frame and have to the other end where they will be discharged and the operation of the machine had upon them, they are both made smooth, made to a width and to a thickness and are in full ready to be laid down into a floor. These are kept to their place by slides and rollers there are 3rd A. 13, Band wheel marked A. 3 $\frac{1}{2}$ and 16 see on the longitudinal section of the machine.
